Patented June 26, 1928.

UNITED STATES PATENT OFFICE.

FRED N. ASHWORTH, OF SOMERVILLE, MASSACHUSETTS.

COLLAR BUTTON.

Application filed April 15, 1927. Serial No. 184,099.

This invention relates to an improved collar button, the object of the invention being to provide a collar button which, in addition to its performing the usual functions of a collar button, is adapted to engage a necktie, such as a four-in-hand, and retain it in position relatively to the collar button and prevent its loosening up while in use.

It is further an object of the invention to provide a collar button which will position the tie so that the button itself will be hidden.

The invention consists in a collar button of the character hereinafter described in the specification and particularly as set forth in the claims.

Referring to the drawings:—

Figure 1 is an enlarged plan of one embodiment of my invention.

Fig. 2 is a sectional elevation taken on the line 2—2, Fig. 1.

Fig. 3 is a sectional elevation taken on line 3—3, Fig. 1.

Fig. 4 is an underneath plan of a modified form of my invention.

Fig. 5 is a sectional elevation taken on line 9—9, Fig. 8. Fig. 6 is a modified form of tie retaining member.

Like numerals refer to like parts in the several views of the drawings.

In the drawings, referring to Figs. 1, 2 and 3, 10 is a collar button consisting of a head 11, a shank 12, and a base 13. The shank 12 is oval in cross section to prevent the button from turning in the collar. 14 is a tie retaining member consisting of two prongs 15 and 16, bent at their upper ends to form hooks 17 and 18 respectively. At their lower ends the prongs 15 and 16 have fastened thereto a push button 19, and between the push button and the head 11, there is positioned within the shank 12 a spiral spring 20, which normally acts to hold the prongs 17 and 18 downwardly against the head 11 and within recesses 21 and 22 respectively, the lower face of the head 19 being normally flush with the lower face of the base 13.

The operation of the device illustrated in Figs. 1, 2 and 3 is as follows:—The button is applied to the front of the shirt, and the front ends of the collar are buttoned thereto in the usual manner. At this time the hook portions of the prongs 15 and 16 lie within the recesses 21 and 22 and, therefore, do not interfere with the convenient manipulation

of the tie. After the tie has been formed into a four-in-hand knot, the user of the device presses on the push button 19 and thus raises the hook portions 17 and 18 of the prongs out of the recesses 21 and 22 and a slight distance away from the head 11. He then inserts the prongs 17 and 18 in the tie by lifting upwardly on the knotted portion of the tie and pressing the material thereof over the prongs. He then releases the push button 19 and the material of the tie is then gripped by the prongs 17 and 18 to the head of the button, so that it cannot loosen up or get out of position.

In Figs. 4 and 5 a modified form of my invention is illustrated in which 38 is the head, 39 the shank and 40 the base of the button. The tie retaining member consists of a single wire 41, which is provided with a hook or prong 42 at the upper end, and has a push button 43 fastened to the lower end, and between the push button and the head 38 and surrounding the wire 41 is a spiral spring 44.

The operation of this device is similar in every way to the embodiment of my invention illustrated in Figs. 1, 2 and 3, the tie retaining member being prevented from rotating in the collar button by the oval shape of the push button 43, which fits into a correspondingly shaped depression 45 in the base 40 of the collar button.

In Fig. 6 a side elevation of a modified form of tie retaining member 46 is illustrated, the same having two prongs and each of these prongs being bent at their upper ends as illustrated in said figure, forming an angular hook instead of a curved hook.

A portion of the top of the collar button is illustrated in Fig. 6 in dotted lines to illustrate the relative location of the tie retaining member 46 to the top of the collar button.

The object of this particular form of hook is to enable the device to be used for bow ties, as it has been found that for a bow tie the angular form of hook is most efficient, especially where a bow tie is used which does not have a strap portion encircling the collar.

In addition to the objects hereinbefore set forth as being accomplished by the device of my invention, it will be understood that it is unnecessary in tying a four-in-hand tie to pull the same tight around the neck. Any form of tie may be utilized and loosely

knotted or tied and retained in position by the device of this invention.

It is also to be understood that if a four-in-hand tie has a tendency to work over to one side or at an angle, the device of this invention can be utilized to correct such a tendency by disengaging the tie from the hooks and moving it to the correct desired position and then causing the hooks to engage the tie again. In other words, the tie can be loosely tied and correctly positioned and held in the correct position desired by the user.

I claim:

- 15 1. A collar button embodying a head, shank and base, a bifurcated tie retaining member projecting through said head and bent at its upper end, a push button fast to the lower end thereof, with its lower

face normally flush with the lower face of 20 the base and a spiral spring positioned in said shank and interposed between said head and push button.

2. A collar button embodying a hollow head, a hollow shank and a base, a tie-retaining member projecting through said head and bent at its upper end to form a hook, a push button fast to the lower end thereof, with its lower face normally flush with the lower face of the base, and a spiral 25 30 spring extending through said shank encircling said tie-retaining member with one end bearing against the inside of said head and the other end bearing against said push button.

In testimony whereof I have hereunto set my hand.

FRED N. ASHWORTH.
